(57) **CLAIM**

The ornamental design for a plate for a boat stand, as shown and described.

DESCRIPTION

FIG. 1 is a perspective view of a bottom side of a plate for a boat stand showing our design.

FIG. 2 is a plan view of the plate for a boat stand.

FIG. 3 is a right side view of the plate for a boat stand, the left side view being a mirror image thereof; and,
FIG. 4 is a front side view of the plate for a boat stand, the rear side view being a mirror image thereof.

The broken lines in the figures are included for the purpose of illustrating portions of the plate for a boat stand and form no part of the claimed design.
